Int. Cl. D26—03

U.S. Cl. D48—20

Fig. 1

Fig. 2

FIGURE 1 is a front perspective view of a combined light for stage and advertising use and control therefor embodying my new design.

FIGURE 2 is a front elevational view in enlarged scale thereof.

FIGURE 3 is a top plan view in enlarged scale thereof.

FIGURE 4 is a rear elevational view in reduced scale thereof.

FIGURE 5 is a bottom plan view in reduced scale thereof.

FIGURE 6 is an elevational view in enlarged scale taken from one side thereof, the opposite side being a mirror image of the side shown.

The dominant features of my design reside in the portions shown in full lines.

I claim:

The ornamental design for a combined light for stage and advertising use and control therefor, substantially as shown and described.
